UNITED STATES PATENT OFFICE.

EBENEZER M. BLISS, OF RIVERSIDE, CALIFORNIA.

FLUSH VALVE.

Application filed May 19, 1926. Serial No. 110,170.

This invention relates to flush valves for flush tanks, such as employed in toilets.

An important object of the invention is to provide a flush valve of improved construction for flush tanks, which will be held open by the water passing therethrough, until the tank is emptied, whereupon the valve will be automatically closed.

Another object is to provide a flush valve in which the valve operating rods and closing springs extend outside of the valve chamber where they are out of contact with the water and thereby protected from the rusting effect of the water.

15 A further object is to provide a valve of the character stated which will be simple in construction and highly practical and efficient in operation.

Other objects and advantages will appear 20 hereinafter.

The invention is illustrated in the annexed drawing which forms a part of this specification and in which:

25 Fig. 1 is a vertical longitudinal section of my flush valve taken on line 1—1 of Fig. 2.

Fig. 2 is a view, showing in side elevation my flush valve and a flush tank to which the valve is connected, and showing in vertical section the pocket in a wall in which 30 said tank is mounted.

Fig. 3 is a fragmentary view of the valve showing certain parts in elevation and other parts in vertical section taken on line 3—3 of Fig. 1.

35 Corresponding reference characters designate the same parts in all the views.

In the drawing 1 designates a casing constructed in a plurality of sections 2, 3, 4 and 5. The section 2 is the lower end section of 40 the casing and in its upper end is screw seated the lower end of the next section 3 as indicated at 6. In the upper end of section 3 is screw seated the lower end of section 5 as indicated at 7. The upper end of 45 section 4 is provided with an internally threaded neck 8 in which is screw seated the plug section 5, said section being provided with a thread 9 for engaging the thread in the bore 8. The section 4 is provided with the 50 valve inlet 10 which is connected by means of a pipe 11 to the lower end of a flush tank 12 which may be mounted in a pocket 13 in a wall. The section 2 is provided in its lower wall with the valve outlet 14 and an 55 outlet pipe 15 is screw connected at 16 to

said section in communication with said outlet.

The section 4 is provided with a lower wall 17 and an upper wall 18 and forms the valve chamber 19. The lower wall 17 of 60 said section is provided with an internally threaded opening 20 to receive an externally threaded valve seat member 21. Said member is provided with a valve opening 22 and with a valve seat 23 in the upper side of the 65 wall surrounding said opening. A valve stem bearing 24 is formed in the lower part of the member 22. A valve 25 is located within the valve chamber 19 and includes a stem 26, the lower portion of which is slidably 70 mounted in the bearing 24, so that the valve may rise above the seat 24 to open position or descend upon said seat into closed position. The lower end wall of the plug section 5 is formed with a bearing 27 in which 75 slides the upper end of the valve stem 26.

The lower end of the valve stem 26 is threaded as indicated at 28 which screws into a threaded socket 29 in the upper end of a valve lifting member 30. A lock nut 31 80 screws on said threaded end of the valve stem against the upper end of said valve lifting member for holding said member against turning. On the lower end of the lifting member 30 is formed a cam 32. A cross 85 bar 33 is provided with an opening 34 through which extends the upper end of the lifting member 30 and a pin 35 extends through said bar and member to hold the bar on the member. To the outer ends of the cross bar 33 are respectively connected a pair of valve lifting rods 36 which extend upwardly through the casing section 4 outside the valve chamber 19 through the bearings 37, in the lower end of said casing, bores 38 extending downwardly in said section to the upper end of said bearings, and screw plug bearings 39 seated in the section 4 in the upper end of said bores. Springs 40 surround the rods 36 in the bores 38 100 bear at their upper ends against the upper bearings 39 and at their lower ends against the collars 41 secured on the rods, which springs, through the rods 36, cross bar 33 and lifting member 30 normally hold the valve 25 on its seat in closed position. The upper ends of the rods 36 are connected to a ring 42 which surrounds the neck 8. An inverted yoke 43 straddles the neck 8 105 and is connected at its ends at 44 to the ring 110

42. On the upper cross member of the yoke 43 is pivoted a lever 45, on the lower end of which is formed a cam 46 for engaging a roller 47 journaled in the bearings 48 on top 5 of the casing plug section 5.

A pair of hangers 49 are suspended from the under side of the casing section 4 at opposite sides respectively of the valve stem 26 and lifting member 30, between the lower 10 ends of which hangers are pivoted at 49' a valve lifting lever 50. On one end of the lever 50 is secured a baffle plate 51 and a weight 52 is adjustably secured on the other end of said lever. A roller 53 is journaled 15 on the upper side of the lever 50 and is normally engaged by the cam 32 under the influence of the springs 36 to hold the lever in its lower horizontal position. The weight 52 is secured on the lever 50 as hereinbefore 20 described, by being mounted upon the pin 56, the pin 56 is in turn slidably positioned in the slots 54, and clamped in adjustable position by the locking nuts 55.

The operation of the invention is as follows:

The valve 25 being closed and the levers 45 and 50 in horizontal position, to open the valve, the lever 45 is raised and the cam 46, engaging the roller 47, raises the 30 valve 25 off its seat, through the medium of the yoke 43, ring 42, rods 36, bar 33, lifting member 30 and valve stem 26, during which operation the springs 38 are compressed and the cam 32 raised above the roller 53. Water 35 then rushes from the tank 12 through the pipe 11 and inlet 10 into the valve chamber 19, through valve opening 20 into the lower part of the valve casing and out through the outlet 14 and pipe 15, during which 40 operation the pressure of the water against the baffle plate 51 swings the lever 50 counter clockwise and the roller 53 directly under the cam 32, (see dotted line 45 position Fig. 1) which holds the valve 25 off its seat until all the water passes out of the tank 12 through the valve, after which the springs 38 force the rods 36, bar 33, lifting member 30 and the valve down until the 50 valve seats itself on the seat 23 and the levers 45 and 50 are swung back into normal horizontal position. While the valve is held raised by the engagement of the roller 53 with the cam 32, the lever 45 is held 55 vertical by the engagement of its cam 46 with the roller 47.

When it is found that the pressure of water against the baffle plate 51 is too strong, or too weak, the leverage of the weight 52 from the pivot 49' may be 60 adjusted by sliding the said weight 52 upon the pin 56 in the slots 54, and then locking the nuts 55 in the adjusted position upon the pin 56 against the lever 50, to control the pressure of water flowing against the 65 plate 51, as hereinbefore described.

Having thus described my invention what I claim is:

1. In a flush valve, a casing formed with a valve chamber in the upper part thereof and provided with an inlet leading into said chamber, a valve opening leading from said chamber, and an outlet, a valve mounted to seat in said opening, valve lifting rods extending outside said valve chamber, collars on said rods, springs on said rods engaging said collars for normally holding said valve on its seat, a yoke, means connecting said yoke and the outer ends of said rods, a cam pivoted on said yoke, and a roller on the upper end of the casing to be engaged by said cam for lifting the valve off its seat. 70

2. In a flush valve, a casing provided with a valve chamber in the upper part thereof and provided with an inlet leading into said chamber, the valve opening leading from said chamber into the lower part of the casing, and an outlet leading from the lower end of the casing, a valve mounted to seat in said opening, means for normally holding the valve on its seat, means for lifting the valve off its seat, a lifting member connected to the valve and extending in the lower part of said casing, a cam on the lower end of said lifting member, a lever in the lower part of the casing, a roller on said lever engaged by said cam to hold the lever in its initial position when the valve is on its seat, and a baffle plate on said lever to be acted upon by the water passing through the valve when the valve is lifted off its seat, to hold the lever in position with its roller engaging said cam to hold the valve off its seat until water ceases to enter the valve. 85

3. In a flush valve, a casing provided with a valve chamber in the upper part thereof and provided with an inlet leading into said chamber, the valve opening leading from said chamber into the lower part of the casing, and an outlet leading from the lower end of the casing, a valve mounted to seat in said opening, a lifting member connected to said valve and extending into the lower part of said casing, a cross bar connected to said lifting member, valve lifting rods extending outside the valve chamber, collars on said rods, springs on said rods engaging said collars for normally holding the valve on its seat, a yoke, means connecting said yoke and the upper ends of said rods, a cam pivoted on said yoke, a roller on the upper end of the casing to be engaged by said cam for lifting the valve off its seat, a cam on the lower end of said lifting member, a lever in the lower part of the casing, a roller on said lever engaged by said cam to hold the lever in its initial position when the valve is on its seat, and a baffle plate on said lever to be acted upon 95 100 105 110 115 120 125 130

by the water passing through the valve when the valve is lifted off its seat to hold the lever in position with its roller engaging said cam to hold the valve off its seat until water ceases to enter the valve.

4. In a flush valve, a casing formed with a valve chamber in the upper part thereof and provided with an inlet leading into said chamber, a valve opening leading from said chamber, and an outlet, a valve mounted to seat in said opening, the casing being provided with bores extending downwardly therein, valve lifting rods extending through said bores, springs on said rods in said bores, collars on said rods engaged by the lower ends of said springs, plugs screw seated in the upper ends of said bores through which said rods extend and which are engaged by the upper ends of said springs for normally holding the valve on its seat, a yoke, means connecting said yoke to the upper ends of said valve lifting rods, a cam pivoted on said yoke, and a roller on the upper end of the casing to be engaged by said cam for lifting the valve off its seat.

5. In a flush valve, a casing formed of a plurality of sections screw connected together, one of said sections being formed with a valve chamber, an inlet leading into said chamber, a valve opening leading from said chamber into the section below, and a neck extending upwardly therefrom, in which neck is screw seated the uppermost section, a valve in said valve chamber for seating in said valve opening, valve lifting rods extending through said valve chamber section outside said chamber, means connecting the rods and the valve, collars on the rods, springs on the rods engaging said collars to normally hold the valve on its seat, a yoke, means connecting said yoke and the upper ends of said rods, a cam on said yoke, a roller engaged by said cam for lifting said valve off its seat, the lowermost section having an outlet, a lifting member connected to the valve and extending in the casing below the valve chamber, a cam on the lower end of said lifting member, hangers secured to the valve chamber section, a lever pivoted to said hangers, a roller on said lever engaged by said cam to hold the lever in its normal position when the valve is closed, and a baffle plate on said lever to be acted upon by the water passing through the valve when the valve is lifted off its seat to hold the lever in position with its roller engaging said cam to hold the valve off its seat until water ceases to rush through the valve.

6. In a flush valve, a casing formed with a valve chamber in the upper part thereof and provided with an inlet leading into said

chamber, a valve opening leading from said chamber, and an outlet, a valve mounted to seat in said opening, valve lifting rods extending outside said valve chamber, means for normally holding said valve on its seat, a yoke, means connecting said yoke and the outer ends of said rods, a cam mounted on said yoke, a baffle plate in said outlet to be actuated by the water passing through the valve, when the valve is lifted off its seat to hold the cam in position, to hold the valve off its seat until the rush of water ceases to pass through the valve, and an adjustable balance means adapted to control the pressure of water against said baffle plate.

7. In a flush valve, a casing formed with a valve chamber in the upper part thereof and provided with an inlet leading into said chamber, a valve opening leading from said chamber, an auxiliary chamber in the lower part of said casing in communication with said valve opening, and an outlet leading from said auxiliary chamber, a valve mounted to seat in said opening, valve lifting rods extending outside said casing from said auxiliary chamber, means for normally holding said valve on its seat, a lifting member adjustably secured to the lower side of said valve, a cam mounted on said lifting member, a lever operatively suspended in said auxiliary chamber, a yoke connecting said lifting member and said valve lifting rods, a baffle plate secured to said lever over said outlet to be actuated by the water passing through the valve when the valve is lifted off its seat to hold the cam in position, to hold the valve off its seat until the rush of water ceases to pass through the valve, an adjustable balance means adapted to control the pressure of water against the baffle plate, and a means for lifting the valve lifting rods and for holding the valve in an open position until the said baffle plate is actuated to close said valve.

8. In a flush valve, a casing formed with a valve chamber in the upper part thereof and provided with an inlet leading into said chamber, a valve opening leading from said chamber, and an outlet, a valve mounted to seat in said opening, an auxiliary valve chamber, valve lifting rods extending outside said auxiliary valve chamber, means for normally holding said valve on its seat, a yoke, means connecting said yoke and the outer ends of said rods, and a means for lifting the valve lifting rods and for holding the valve in an open position until the flow of water through said valve opening ceases.

In testimony whereof I hereunto affix my signature.

EBENEZER M. BLISS.
